UNITED STATES PATENT OFFICE.

CHARLES CLARENCE POOLE, OF WINNETKA, ILLINOIS, ASSIGNOR TO THE OLIVER
TYPEWRITER COMPANY, OF CHICAGO, ILLINOIS, A CORPORATION OF ILLINOIS.

COLUMN-STOP MECHANISM FOR TYPE-WRITING MACHINES.

1,110,144.

Specification of Letters Patent.

Patented Sept. 8, 1914.

Application filed January 19, 1914. Serial No. 812,958.

To all whom it may concern:

Be it known that I, CHARLES CLARENCE POOLE, a citizen of the United States, and a resident of Winnetka, in the county of Cook and State of Illinois, have invented certain new and useful Improvements in Column-Stop Mechanism for Type-Writing Machines; and I do hereby declare that the following is a full, clear, and exact description thereof, reference being had to the accompanying drawings, and to the letters of reference marked thereon, which form a part of this specification.

This invention relates to an improved tabulating or column stop mechanism for typewriting machines designed to effect the release of the carriage from the control of the usual letter-spacing devices and permit the carriage to move, under the action of its actuating spring, to a predetermined point or points, at which the movement of the carriage is arrested, for the purpose of printing a series of items or numbers in one or more vertical lines or columns upon the sheet.

The invention relates more particularly to that class of column stop devices which embrace a spring-barrel through which the carriage is actuated and a brake-mechanism, operated by the column-stop key-lever, and acting on the spring-barrel for preventing undue shock or jar when the motion of the carriage is arrested by the action of the column-stop devices.

The invention is herein shown as applied to a typewriting machine of the kind known as the "Oliver" machine, but the features constituting my invention may be applied to machines of other kinds.

The invention consists in the matters hereinafter set forth and pointed out in the appended claims.

In the accompanying drawings illustrating my invention: Figure 1 is a plan view of the machine frame, with the paper-carriage, type-bars and other parts removed, showing only the parts to which the present invention relates; Fig. 2 is a view in central longitudinal section, showing in side elevation the parts of the machine embodying the invention; Fig. 3 is a bottom view of the machine base or frame, showing only the parts connecting the column-stop key-lever

with the brake-device on the spring-barrel; Fig. 4 is a view from beneath of the spring-barrel and brake-shoe; Fig. 5 is a side view of the parts shown in Fig. 4.

As shown in said drawings, 5 (Figs. 1 and 2) indicates the main frame or base of a typewriting machine, and 4 indicates the shift-frame by which the paper-carriage is immediately supported and which has shifting movement backwardly and forwardly on said base. The paper-carriage has endwise or letter-space movement on said shift-frame and said shift-frame has backward and forward movement on the base to provide for shifting the platen in such manner as to bring the paper in position for receiving impressions from two or more types upon each type-bar of the machine. The base 5, as shown, consists of a horizontal top-plate 6, provided with depending marginal walls or flanges 7, forming a hollow frame member within which operative parts of the machine are located.

The key-levers 3, 3 of the machine are located beneath the horizontal top-plate 6 of the base 5, and the shift-frame 4 is mounted above the top-plate of the base, as in the "Oliver" typewriting machine, as heretofore constructed. Said shift-frame is provided with front and rear horizontal guide-rods 4^a and 8, extending transversely of the machine, on which travel the supporting rollers of the carriage. The frame of said carriage embraces a forward longitudinal frame bar 10, which constitutes the rack-bar thereof and is provided on its front edge with rack teeth 11 which are engaged by a gear-pinion 12 mounted on the upper end of an upright escape-wheel shaft 13 mounted on the forward part of the shift-frame. Said escape-wheel shaft 13 forms part of the escape-mechanism which is operated by the universal bar of the machine and by which is controlled the endwise or letter-space movement of the carriage under the action of the carriage-actuating spring. The upper end of said escape-wheel shaft, with the gear-pinion 12 thereon, is adapted to be moved or shifted forwardly and backwardly to bring the gear-pinion into and out of engagement with the rack teeth 11.

100 and the upper end of said shaft is held yieldingly at the rearward limit of its movement

by a suitably applied spring, according to the construction in the "Oliver" machine as now made.

The column-stop or tabulating mechanism to which the present invention relates, includes means for releasing the carriage from the letter-spacing mechanism, and for arresting the movement of the carriage, when so released, at predetermined points in its travel, the devices for this purpose illustrated being like those shown in the prior patent to Knapp and Harting, No. 959,061, of May 24th, 1910, and embracing features as follows: The front frame-member or rack-bar 10 of the paper-carriage is provided with a depending, longitudinal flange 18, provided at its lower edge with a plurality of notches. Mounted on said flange 18 are adjustable stop-members 20. A vertically movable stop-member 21 is attached to the rear end of a vertically swinging lever 22 mounted on the shift-frame. A vertically arranged plate 33 is attached to the forward end of the bracket 17, and said plate is provided with forwardly extending lugs through which is inserted a horizontally arranged pivot-rod 24, forming a journal or bearing for the said lever 22. The lever 22 is provided at its forward or pivoted end with forwardly and upwardly projecting, rigid arms 25 and 26. To limit the upward swing of the lever 22 when the stop-member 21 is elevated and in the path of the stop-members 20, a horizontal stop-arm 27 is attached to the top surface of the shift-frame and projects forwardly over the rear end of the said lever.

A key-lever 28, for operating the column-stop devices, is mounted on the pivot-rod 24, so as to swing on an axis concentric with the pivot of the lever 22, and projects forward from said bracket. Said key-lever is provided with a stud 29 which projects from the right-hand face thereof in position to engage the under side or lower edge of the forwardly projecting arm 25 on the lever 22. Said key-lever 28 is connected with the upwardly extending arm 26 of the lever 22 by means of a contractile, coiled spring 30 connected at one end with said arm 26 and at its opposite end with a stud 31 affixed to and projecting from the right-hand side of said key-lever. Said spring 30 tends to draw the upper end of the arm 26 forward and to hold the arm 25 in contact with the stud 29 on the key-lever. Said key-lever 28 is provided with a coiled lifting spring 32, which is connected at its lower end with the stud 31 and at its upper end with an arm 33, attached to the bracket 17.

The key-lever 28 is held normally in its elevated position by the spring 32, and said key-lever is provided at its rear or pivoted end with an upwardly extending, rigid arm

35, the upper end of which acts on a horizontally arranged connecting bar 36, engaging the upper end of the escape-wheel shaft 13. Said arm 35 is connected with said bar 36 by means of a longitudinal slot in said bar through which the upper end of said arm of the key-lever upwardly projects; the front and rear edges of the arm being adapted for contact with the opposite ends of the said slot, which is made long enough to afford a slight degree of lost motion between the key-lever and the said bar. In the normal or elevated position of said key-lever 28, the upper end of its arm 35 stands in a position intermediate between the ends of the slot in the connecting bar 16 (Fig. 2), so as to leave said bar free to be moved forwardly with the upper end of the escape-wheel shaft 13, when the latter is swung forwardly to disengage the pinion 12 from the carriage rack, in the operation of the carriage release device on the paper-carriage, usually employed in machines of this character. When said key-lever 28 is depressed by downward pressure of the finger on its key, the lever 22 and the stop-member 21 thereon are swung or moved with the key-lever, through the action of the spring 30, so as to lift the stop-member into the path of the stop-members 20 on the carriage. The movement of said lever 22 with the key-lever continues until the upward movement of said lever is arrested by its contact with the stop-arm 27, and, in the further downward movement of said key-lever, the arm 35 thereon will strike the outer end of the slot in the bar 36, when the upper end of the escape-wheel shaft will be drawn or shifted outwardly or forwardly, thereby releasing the pinion 12 from the carriage rack-bar and leaving the carriage free to travel or run toward the left, under the action of the carriage-actuating spring, until its movement is arrested by contact of one of the stops 20 with the stop-member 21. So far as described, the column-stop mechanism is like that heretofore used on said "Oliver" machine.

In order to avoid undue shock or jar when the movement of the carriage is arrested by the action of the column-stop mechanism, means for retarding or controlling the speed of the paper-carriage, when released and allowed to run, as described, is provided as follows: The spring-barrel 40 of the machine contains the carriage-actuating spring, and motion is communicated from said spring-barrel to the carriage by a flexible connecting member 41 in a familiar manner. Said spring-barrel 40 is mounted on the upper face of the horizontal top-plate 6 of the machine base, near the rear of said base and at the left-hand side of the same. The spring-barrel is shown as provided with a worm-gear, consisting of a horizontal worm-

shaft 42 and gear-wheel 43, by which the tension of the carriage-actuating spring may be adjusted. The gear-wheel 43 is located beneath the spring-barrel, and the worm-shaft 43 is mounted in a hub 44, formed on a horizontal plate 45 attached to the plate 6, beneath the spring-barrel. A segmental plate or ring 46, constituting a brake-member, is located horizontally beneath the 10 spring-barrel. Said brake-member 46 is loosely connected at one point with the machine base, through the medium of an upwardly projecting, fixed arm 47 formed on the plate 45 and located at one side of the 15 spring-barrel; the upper end of said arm 47 being inserted in an aperture in the brake-member 46, and being provided with upwardly facing shoulders, below the brake-member, adapted to support the latter at a 20 short distance below the spring-barrel. At the side of the barrel diametrically opposite the arm 47, the plate constituting the brake-member is provided with an arm 48, the outer end of which is arranged horizontally 25 and adjacent to the top-plate of the base. The ends of the segmental plate 46 terminate at diametrically opposite ends of the spring-barrel, and are bent upwardly to form two bearing members or brake-shoes 49, 49. The 30 brake-shoes 49, 49, and the outer end of the arm 47, are adapted to move or swing vertically by the swinging of the brake-member on the upper end of the arm 47 as a bearing or pivot. These parts are so arranged that, 35 by upward pressure on said arm 47, the brake-shoes 49, 49 will be pressed upwardly against the bottom surface of the spring-barrel, so as to afford frictional resistance to the rotation of said barrel under the action 40 of the carriage-actuating spring.

The brake-member 46 is operated or actuated, from the column-stop key-lever 28, by means as follows: Mounted within the hollow base 5 of the machine, below the level 45 of the key-levers 8, 8, and therefore at a considerable distance below the horizontal top-plate of the base, is a motion-transmitting lever consisting of a horizontal rock-shaft 50, extending transversely of the machine 50 and provided at its ends with two rigid arms 51 and 52, the outer ends of which are adapted to have vertical swinging movement in the turning of the said rock-shaft. The said rock-shaft is shown as mounted at 55 its ends in two brackets 53 and 54 which are attached to and depend from a fixed frame-bar 55 which extends transversely of the machine beneath the key-levers 8, 8, as shown in the prior patent, No. 908,823, granted to 60 T. L. Knapp, November 10, 1908. The lever arm 51 extends forwardly from the rock-shaft 50, and its forward or swinging end is located vertically beneath the column-stop key-lever 28. The lever-arm 52 extends rear-

wardly from said rock-shaft and its rear end is located beneath the spring-barrel 40. The forward end of the lever-arm 51 is connected with the said key-lever 28, by means of a vertically arranged link 56, which is pivoted at its upper end to the said key-lever 70 and at its lower end to said lever-arm. Said link serves to transmit movement from the said key-lever 28 to the lever-arm 51, so that when the key-lever is depressed for the purpose of effecting the release of the carriage 75 and the interposition of the movable stop-member in the path of one of the stops on the carriage, the said lever-arm 51 will be depressed and the rearwardly extending lever-arm 52 will be elevated. Attached to 80 the rear end of said rearwardly extending lever-arm 52 is an upright rod 57, which extends upwardly through a hole or guide-aperture 58 (Fig. 5), in the top-plate of the machine base, in position for contact of its 85 upper end with the arm 48 on the brake-member 46. It follows from the construction described that, when the lever-arm 52 is elevated by the operation of the column-stop key-lever, the brake-shoes will be lifted 90 and pressed into contact with the spring-barrel, thereby checking or retarding the rotary motion of the same and the endwise movement of the paper-carriage.

It will be understood that, by reason of 95 the location of the actuating lever-arms 51 and 52 below the key-levers, and near the level of the bottom of the hollow machine base, the link 56 will be of considerable length, and the pivot connecting said link 100 with the lever-arm 51 is at such distance vertically below the key-lever 28, that the forward-and-backward shifting movement of the last named key-lever, with the shift-frame on which it is mounted, will give such 105 slight vertical movement to, or shifting of the position of, the upper end of the said link, as to have substantially no effect on the operation of the brake-mechanism.

In other words, by reason of the slight in- 110 clination given to the link at the extreme limit of the shifting movement of the shift-frame, the brake-device will operate equally well, whether the shift-frame be at its intermediate position, or at either the forward or 115 rear limit of its shifting movement, such as takes place in shifting the platen into position for printing from either one of the three types carried by each type-bar in a machine of this character.

A brake-device for a column-stop or tabulating mechanism, embracing the features of construction hereinbefore described, may be used in connection with carriage-releasing means different from that illustrated, and 125 may be variously modified in practice with regard to its details of construction, without departing from the spirit of my invention,

and my invention is not, therefore, limited to the features described and shown, except as pointed out in the appended claims.

I claim as my invention:

- 5 1. In a typewriting machine, the combination of a base-frame, key-levers mounted thereon, a shift-frame, a paper-carriage movable on the shift-frame, a spring-barrel mounted on the base-frame, column-stop mechanism for releasing the carriage from the letter-spacing mechanism and arresting its movement at a desired point, embracing a key-lever mounted on the shift-frame, brake-mechanism adapted to act on the 10 15 20 25 30 35 40 45 50 55 60 65 70 75 80 85 90 95 100 spring-barrel, and means for actuating the brake-mechanism embracing motion-transmitting means mounted on the base-frame at a distance below the said key-lever, and a vertically arranged link having pivotal connection at its upper end with said key-lever and at its lower end with the motion-transmitting means, the upper end of said link being movable forwardly and backwardly with the said key-lever in the shifting movement of the shift-frame.

2. In a typewriting machine, the combination of a base-frame, key-levers, a shift-frame, a paper-carriage movable on the shift-frame, a spring-barrel mounted on the base-frame, and column-stop mechanism for releasing the carriage from the letter-spacing mechanism and arresting its movement at a desired point, embracing a key-lever mounted on the shift-frame, brake-mechanism mounted on the base-frame and acting on the spring-barrel, and means for actuating the brake-mechanism embracing a motion-transmitting lever mounted on the base-frame below the said key-lever, said lever having a vertically swinging arm located below the said key-lever, and a vertically arranged link pivoted at its upper end to said key-lever and at its lower end to the said arm, the upper end of said link being movable forwardly and backwardly with the said key-lever in the shifting movement of the shift-frame.

3. In a typewriting machine, the combination of a hollow base consisting of a horizontal top-wall and side walls, key-levers located below the level of the top-wall, a shift-frame mounted on the base above the top-wall, a paper-carriage mounted on the shift-frame, means actuating the carriage

for letter-spacing, embracing a spring-barrel mounted on the top-wall of the base, a column-stop key-lever mounted on the shift-frame, brake-mechanism for the spring-barrel, and means for actuating said brake-mechanism from the column-stop key-lever, comprising a pivoted actuating lever mounted within the hollow base below the said key-lever, and having vertically swinging arms, one of which extends forwardly to a point vertically below the said key-lever, and the other of which extends rearwardly to a point below the brake-mechanism, a vertically arranged link having pivotal connection at its upper end with the said key-lever; and at its lower end with the forwardly extending arm of the actuating lever, and means for transmitting motion from the rearwardly extending arm of said actuating lever to the brake mechanism.

4. In a typewriting machine, the combination with a hollow base having a top-wall, of a shift-frame, a paper-carriage mounted on the shift-frame, means actuating the carriage for letter-spacing, embracing a spring-barrel mounted on the rear part of the base above the top-wall, a column-stop key-lever mounted on the shift-frame, a brake-member connected with the top plate of the base and adapted to bear against the lower surface of the spring-barrel, a pivoted actuating lever mounted on the machine frame below the top plate and having vertically swinging arms, one of which extends forwardly to a point below the column-stop key-lever and the other of which extends rearwardly to a point below the spring-barrel, a vertically arranged link pivotally connected at its upper end with said key-lever and at its lower end with the forwardly extending arm of the actuating lever, and a vertically arranged rod connected at its lower end with the rearwardly extending arm of said actuating lever and extending upwardly through the top-plate of the base, with its upper end in position to act on said brake-member.

In testimony, that I, claim the foregoing as my invention I affix my signature in the presence of two witnesses, this 17th day of January A. D. 1914.

CHARLES CLARENCE POOLE.
